SAXOPHONE

Hector Sommaruga, London, England

Application February 27, 1947, Serial No. 731,335
In Great Britain December 14, 1945Section 1, Public Law 690, August 8, 1946
Patent expires December 14, 1965

3 Claims. (Cl. 84—385)

1

This invention relates to saxophones and like musical instruments, the saxophone being a musical instrument comprising a tubular body formed with valve apertures (otherwise known as tone holes) in association with which are provided valves and valve-actuating keys. It is to be understood that the improved form of saxophone herein described is taken as an exemplary embodiment of the invention: it is practicable to embody the invention alternatively in other wind instruments which are analogous to the saxophone by reason of being of the same key-controlled type.

The object of the invention is to produce saxophones or the like provided with key work of novel construction, which is advantageous in that it is much simpler than the normal construction, that it facilitates initial assembly of the instrument and that, in preferred embodiments, it also facilitates repair.

The term "key-work" designates collectively a plurality of keys and valves together with the means for supporting these, means for interconnecting certain keys and valves and means for biasing them to predetermined positions of rest, such several means comprising an axle or axles, upon which the valves and keys or key levers are pivoted and which is or are carried by supporting pillars, and also comprising bridge-work (where necessary) and biasing springs. The term "bridge-work" designates collectively such parts of the key work as provide actuating interconnection between individual keys and valves remote from said keys but intended to be actuated by them. As is known, some of the valves are actuated by direct fingering of the valve "cup" and others through the agency of a key lever connected with the pivot arm of the valve cup or otherwise associated with the valve, either directly or indirectly. Thus, for instance, where a valve is required to pivot in opposite sense to a key lever which actuates it, the motion may be transmitted indirectly. An individual "bridge" is an elongated rod-like member extending in substantial parallelism with an axle about which it pivots: when rocked by a key-lever attached to it, such bridge transmits the motion for actuating one or more of the said valves.

According to the invention, a saxophone or like key-controlled wind instrument has at least a part of its key-work (as hereinbefore defined) constructed as a self-contained unit which is adapted to be preassembled and subsequently fixed, by means of two or more pillars or parts of pillars, to the body of the instrument.

2

It is preferred to make the said pillars or parts of pillars easily detachable from the instrument body, so as to allow the unit to be removed from the body with its axle or axles, valves, keys and springs all in their proper relative positions: this avoids the need for dismantling every key, as it is now necessary to do when repairs have to be undertaken.

The saxophone in its most commonly used forms (e. g. alto and tenor) comprises a long hollow conical body, of which about two-thirds of the length from the smaller diameter is straight whilst the end of larger diameter is doubled back to lie adjacent to the straight part, the back-turned part being known as the bell.

Usually more than 30 pillars are soldered on the body, some of these pillars being used to support the axles on which the keys pivot, and some serving to hold more than 20 needle springs, which are necessary to return the keys to their normal positions of rest after fingering.

The invention, however, provides for greatly reducing the number of pillars, altering their shape and their positions on the body, introducing a different springing system and shaping the key-work to suit the different springing and the different arrangement of pillars. As a subsidiary feature, the invention provides a novel arrangement of the guards used to protect vulnerable parts of the key-work.

In embodying these modifications in a saxophone, many departures may be made from customary constructional practice. For example, with only few exceptions, all the keys and valves necessary for the playing of the saxophone may be grouped into two main units: a left hand unit for the upper part of the instrument, and a right-hand unit for the lower part. A few pillars of novel formation (two only, in the simplest cases) suffice, in each unit, to support the axle or axles carrying all the valves and keys of the unit. The springs, instead of being mounted on separate pillars, may be so formed as to permit of their being threaded on the axle or axles on which the keys and valves pivot, such springs may then find fixed abutments on the instrument body. Thus a plurality of springs can be threaded, together with the arms of their corresponding valves, for instance, upon a single axle between two pillars. Thereby a number of spring-carrying pillars are eliminated, so that the construction of the instrument is greatly simplified.

Instead of having as is normally done now, a number of small guards, giving individual protection to keys that are placed in vulnerable po-

sitions on the instrument, a single detachable guard may be provided for each whole unit of keys: moreover, such guard, besides protecting all the keys of the unit, may also act as a key regulator or stop for the pivoted valves. The guard may be added after the key-work is mounted, and provisions for securing it may be made either on the pillars or on the instrument body.

Locating holes, recesses or projections may be provided in or on the body to receive the pillars or pillar-parts, which may be screwed in position or secured by any other suitable means. As a rule it is preferred to have the locating means made integral with the body. Thus, in the case of sheet metal bodies, lugs may be brazed or soldered in position or recesses may be produced by pressing, whereas if the body be made in the form of a moulding, as disclosed in my co-pending British patent application No. 33,958 of 1945, such lugs or recesses may be produced in the moulding operation. In particular instances it may happen that the shape or position of a lug or other pillar-receiving projection is such that to mould it integrally with the body would necessitate the use of a moulding tool of unduly complicated and expensive construction. To overcome this difficulty, one or more of the pillar-receiving and locating parts may, when necessary, be made separately from the instrument body and subsequently screwed to said body in the required position or positions.

The accompanying drawings serve to show, by way of example, how the features of the invention may be embodied in the construction of a left-hand key mechanism for a saxophone.

In these drawings:

Figure 1 is a perspective view, in the nature of a general arrangement, showing part of the straight tapering tubular element of a saxophone body with unitary left-hand key-work mounted thereon.

Figure 2 is a perspective view showing part of the straight tubular body element and part of the unitary key-work detached from said element and turned through about 90° to show especially the underside of the detachable pillars. Some of the valves and keys have been omitted for clearness of illustration: moreover the body part has been drawn without the various tone holes with which it must be pierced to bring it to its finished condition.

Figure 3 is a fragmentary and sectioned perspective view showing part of a moulded body tube with a tone hole and valve contacting therewith: this figure also shows part of the bridge-work and part of a guard unit.

Figure 4 is an enlarged cross sectional view of a moulded body tube, a valve and a biasing spring for said valve.

Figure 5 is a detail perspective view of the biasing spring shown in side view in Figure 4.

Figure 6 is a perspective view showing a detachable pillar and part of a body tube having an integral locator lug for said pillar.

Figure 7 is another perspective view showing a body tube and an alternative form of pillar, part of which is detachable.

Figure 8 shows in cross section, a fragment of a body tube with a screwed on locator bracket adapted to receive a detachable pillar.

Referring to these drawings; the reference 1 denotes the straight tapering tubular member of a saxophone body which, if thin-walled, will ordinarily be made in sheet metal but which may advantageously be produced by a moulding oper-

ation in accordance with the invention disclosed in my co-pending patent application No. 33,958 of 1945 aforesaid. This body member is pierced by a number of tone holes 2 (omitted from Figures 2 and 6) which are adapted to be closed by valves 3 each consisting of a pivotally mounted cup holding an obturating pad 4, which can co-operate with a valve seating 5, as best seen in Figure 4. Each valve has an arm 6 whereby it is pivoted on an axle 7 or 8 (Figure 1).

At 9, 9a, 9b and 9c are indicated various different fingering keys for actuating the valves, as required in the playing of the instrument. Keys such as 9 are mounted directly on the cups of normally open valves: other keys 9a, 9b, are mounted on levers 10 pivoted upon one or the other of the two axles shown in the present example. Key 9c is selected as an example of a key which has to be connected to its valve 3 by way of a bridge member 11. A number of such bridge members are indicated at 11 in Figures 2 and 3, some of these, instead of connecting directly with a valve-arm 6 pivoted on the same axle as the key lever, may terminate in a lug or cam, adapted for tilting the arm of a valve separately pivoted upon the same axle or upon the other axle.

Figure 5 shows a preferred form of valve-biasing coil spring 12 which can be threaded on to an axle together with the valve which it has to bias and Figure 4 shows how one arm of such spring can act on a valve arm 6 (tending to move the valve to the open position) while the other arms of said spring find a fixed abutment against a shoulder 13 of the body tube. It will also be observed (see Figures 1 and 2) that the valve arms 6 are slotted or bifurcated in their pivoted regions and that the convolutions of the springs 12 are located within the resulting gaps 14.

The axles 7 and 8 carrying all the pivoted key-work thus far described are mounted on the instrument body with the aid of two terminal pillars 15 and 16, bored as at 17 and 18 (Figure 6), to receive the ends of said axles: these pillars are detachably secured respectively to locator lugs 19 and 20 integral with the body 1. Figures 2 and 6 show how the bases of the pillars are shaped to fit over the locator lugs and how they have holes 21 adapted to align with bores 22 in the lugs, so that a screw or a cotter can be driven through to fix the said pillars and, therewith, to locate the whole of the unitary key-work on the body. Assuming accurate pre-assembly of the valves, springs and keys upon the axles the fixing of the pillars with the axles between them will locate the working parts accurately in relation to the body, although, if necessary, provision may be made for minor adjustments of the valves relatively to the tone holes. If desired particularly in the case of long key-work units, intermediate, auxiliary pillars, such as 23 and 24 may be threaded on to the axles at the time of assembling the mechanism and subsequently fixed to locator lugs 25 and 26 on the body.

It will be obvious that, so long as the several pillars are not fixed in permanent fashion to the locator lugs, the whole unit can readily be removed for repair or replacement by a similar pre-assembled unit.

The alternative pillar construction depicted in Figure 7 is suited to a less elaborate key-work unit requiring only a single axle, as 27. Here each of the two main pillars comprises two parts, of which the part 28 is integral with the body 1 and

serves to locate the detachable part 29, which latter has pierced lugs or flanges 29' by means of which it can be pinned or screwed to said part 28. The plane of division between the two pillars parts coincides with the axis of the axle 27 and semi-cylindrical recesses 30 and 31 in the confronting faces of the said parts come together to form seatings or clamping surfaces for the ends of the said axles when the latter (with the valves and keys which it carries) is being mounted in position on the body.

Adverting to Figures 1 and 3, the reference 32 denotes a unitary guard member which extends between the main pillars 15 and 16 covering the axles and all the more vulnerable parts of the pivoted mechanism. As illustrated, this guard is part-cylindrical in cross-section and its ends overlap and embrace the said main pillars, which are also flanged, as at 33 to locate said guard in endwise direction. At least one longitudinal edge of this guard may be channelled, as at 32' to receive a buffer strip 34 of slightly yielding material, adapted to act as a stop for the valve levers 6 and, it may be, for some of the key-levers 10. The guard may be secured to the body or to the pillars: according to Figure 1 the pillars 15 and 16 have side lugs 35 to which the stop portion of the said guard may be fixed as by screws 36 and these attaching means may embody an adjustment whereby the level of the buffer strip 34 can be set to suit the degree of opening permitted to the valve 3.

Figure 8 shows how locator lugs or brackets for the pillars may be fixed by screw means in the positions which they are to occupy; this mode of construction is especially applicable to moulded bodies in cases where it is desired to avoid having to use an unduly complicated moulding tool. A locator bracket 37, of channel section, has the underside of its web-portion 37' curved to the radius of the body tube 1, which latter is shown as having a slight depression 1' in its exterior to help in positioning the said bracket. A saddle-plate 38, which can be introduced into the tube, has an upstanding threaded stud 39, which latter is passed through registering holes in the body-wall and web 37' to receive a nut 40, whereby the assembly is tightly clamped together.

By virtue of the invention it is possible to manufacture a saxophone or like wind instrument possessing all the conventional playing facilities yet having a more pleasing appearance, greater sturdiness, and less liability to break down and all this at a greatly reduced cost of production.

I claim:

1. In a saxophone a tubular member, tone holes disposed at intervals along said member, locator lugs integral with said tubular member, terminal pillars detachably secured to said lugs, an axle secured at its ends to the said pillars, and an assembly of valves for the tone holes together with springs and keys therefor assembled on said axle as a unitary detachable assembly.
2. In a saxophone a tubular member, tone holes disposed at intervals along said member, locator lugs integral with said member, terminal pillars detachably secured to said lugs, axles supported in said pillars, a guard shrouding the axles, valves normally closing the tone holes and connected to said axles by means passing under the guard, springs on the axles loading the valves to the closed position, and keys operatively connected to the valves.
3. In a saxophone, a tubular member, tone holes disposed at intervals along said member, locator lugs integral with the pillar, terminal pillars slidably engaged over and detachably secured to said lugs, axles secured in said terminal pillars, additional locator lugs formed on the tube between said terminals lugs, corresponding additional pillars detachably secured to said latter lugs and receiving said axles, valves normally closing said tone holes, means connecting the valves to the said axles, an inverted channel section guard shrouding the axles and secured to said pillars, a buffer strip along one edge of said guard acting as a buffer for the means connecting the valves to the axles, springs on the axles loading the valves to the closed position, and keys carried by said axles for operating the valves, the said pillars, axles, valves and associated means and the said guard being detachable as a unit from the said tubular member.

40

HECTOR SOMMARUGA.
